FIG. 4 is a left side elevational view thereof;
FIG. 5 is a right side elevational view thereof;
FIG. 6 is a top plan view thereof; and
FIG. 7 is a bottom plan view thereof.
FIG. 8 is an enlarged partial left side elevational view thereof along the lines 8-8 of FIG. 4.
FIG. 9 is a perspective view of a second embodiment of a memory card showing my new design;
FIG. 10 is a front elevational view thereof;
FIG. 11 is a rear elevational view thereof;
FIG. 12 is a left side elevational view thereof;
FIG. 13 is a right side elevational view thereof;
FIG. 14 is a top plan view thereof; and
FIG. 15 is a bottom plan view thereof.
FIG. 16 is an enlarged partial left side elevational view thereof along the lines 16-16 of FIG. 12.
FIG. 17 is a perspective view of a third embodiment of a memory card showing my new design;
FIG. 18 is a front elevational view thereof;
FIG. 19 is a rear elevational view thereof;
FIG. 20 is a left side elevational view thereof;
FIG. 21 is a right side elevational view thereof;
FIG. 22 is a top plan view thereof; and
FIG. 23 is a bottom plan view thereof.
FIG. 24 is an enlarged partial left side elevational view thereof along the lines 24-24 of FIG. 20.
FIG. 25 is a perspective view of a fourth embodiment of a memory card showing my new design;
FIG. 26 is a front elevational view thereof;
FIG. 27 is a rear elevational view thereof;
FIG. 28 is a left side elevational view thereof;
FIG. 29 is a right side elevational view thereof;
FIG. 30 is a top plan view thereof; and
FIG. 31 is a bottom plan view thereof.
FIG. 32 is a partially enlarged left side elevational view thereof along the line 32-32 of FIG. 28.
FIG. 33 is a perspective view of a fifth embodiment of a memory card showing my new design;
FIG. 34 is a front elevational view thereof;
FIG. 35 is a rear elevational view thereof;
FIG. 36 is a left side elevational view thereof;
FIG. 37 is a right side elevational view thereof;
FIG. 38 is a top plan view thereof; and
FIG. 39 is a bottom plan view thereof.
FIG. 40 is a partially enlarged left side elevational view thereof along the line 40-40 of FIG. 36.
FIG. 41 is a perspective view of a sixth embodiment of a memory card showing my new design;
FIG. 42 is a front elevational view thereof;
FIG. 43 is a rear elevational view thereof;
FIG. 44 is a left side elevational view thereof;

FIG. 45 is a right side elevational view thereof;

FIG. 46 is a top plan view thereof; and

FIG. 47 is a bottom plan view thereof.

FIG. 48 is a partially enlarged left side elevational view thereof along the line 48-48 of FIG. 44.

FIG. 49 is a perspective view of a seventh embodiment of a memory card showing my new design;

FIG. 50 is a front elevational view thereof;

FIG. 51 is a rear elevational view thereof;

FIG. 52 is a left side elevational view thereof;

FIG. 53 is a right side elevational view thereof;

FIG. 54 is a top plan view thereof; and

FIG. 55 is a bottom plan view thereof.

FIG. 56 is a partially enlarged left side elevational view thereof along the line 56-56 of FIG. 52.

FIG. 57 is a perspective view of an eighth embodiment of a memory card showing my new design;

FIG. 58 is a front elevational view thereof;

FIG. 59 is a rear elevational view thereof;

FIG. 60 is a left side elevational view thereof;

FIG. 61 is a right side elevational view thereof;

FIG. 62 is a top plan view thereof; and

FIG. 63 is a bottom plan view thereof.

FIG. 64 is a partially enlarged left side elevational view thereof along the line 64-64 of FIG. 60.

FIG. 65 is a perspective view of a ninth embodiment of a memory card showing my new design;

FIG. 66 is a front elevational view thereof;

FIG. 67 is a rear elevational view thereof;

FIG. 68 is a left side elevational view thereof;

FIG. 69 is a right side elevational view thereof;

FIG. 70 is a top plan view thereof; and,

FIG. 71 is a bottom plan view thereof.

The even-dash broken lines illustrating a portion of the memory card form no part of the claimed design. Dot-dash broken lines showing of a part of the memory card define the boundaries of the claimed design and are not included in the claimed design.
